EDOUARD GOUTINK, OF DETROIT, MICHIGAN.

Design No. 4,963, dated May 30, 1871.

DESIGN FOR CENTER-PIECE IN CEILINGS.

The Schedule referred to in these Letters Patent and making part of the same.

To whom it may concern:

Be it known that I, EDOUARD GOUTINK, of Detroit, in the county of Wayne and State of Michigan, have invented a new and useful Improvement in Design for Center-Piece in Ceilings; and do declare that the following is a true and accurate description thereof, reference being had to the accompanying photograph.

The nature of my design is fully represented in the accompanying photographic illustration, to which reference is made.

I claim as my invention—

The design for a center-piece for ceilings, as shown.
EDOUARD GOUTINK.
